(57) **CLAIM**

The ornamental design for a vertical blind hanger, as shown and described.

DESCRIPTION

FIG. 1 is a perspective view of a vertical blind hanger showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, shown in a position of use with environmental subject matter.

The evenly spaced broken lines illustrating the vertical blinds depict environmental subject matter that forms no part of the claimed design. The dash-dot-dash broken lines depict the boundaries of the claim and form no part thereof.
